DESIGN.

—o—

W. L. JACOBS.

CARPET.

No. 17,485.

Patented July 26, 1887.

UNITED STATES PATENT OFFICE.

WINTHROP L. JACOBS, OF EAST ORANGE, NEW JERSEY, ASSIGNOR TO THE
HARTFORD CARPET COMPANY, OF HARTFORD, CONNECTICUT.

DESIGN FOR A CARPET.

SPECIFICATION forming part of Design No. 17,485, dated July 26, 1887.

Application filed June 15, 1887. Serial No. 241,433. Term of patent 3½ years.

To all whom it may concern:

Be it known that I, WINTHROP L. JACOBS, of East Orange, New Jersey, have invented a new and original Design for Carpets, of which 5 the following is a specification, reference being had to the accompanying photograph, which forms a part of the same.

The invention relates to a design to be worked into or upon surfaces, such as carpets 10 or similar fabrics; and it consists in the novel configuration and grouping of figures, herein specifically shown and claimed.

The accompanying photograph is a face view of a carpet showing my new design.

15 The main feature of my design is the pendent or hanging work connected with the mass of the figures composing the design. The figures are ornamented with geometrical forms resembling Grecian key-work.

20 Figure A is a somewhat serpentine figure, and its pendent work is coral in its character.

In Figure B the hanging work is varied from single stems to branched stems of differing outlines.

In Figure C in addition to the pendent work 25 below, there are stems projecting from the upper side of the figure, making the outline of the upper side resemble in some measure the outline of the lower side.

Figure D (shown at the upper and lower right-hand corners of the photograph and at the left center) has two parts running nearly at right angles with each other, and having pendent work within the angular space or opening as well as on the lower side of the figure. 30

The various figures are all clearly shown in the photograph in all their details.

What I claim as new, and desire to secure by Letters Patent, is—

35 The design for carpets, consisting of the design substantially as shown.

W. L. JACOBS.
